PNEUMATIC LIFE PRESERVER BELT

Edward C. Craig and Lloyd A. Straits,
United States Navy

Application July 30, 1942, Serial No. 452,822

1 Claim. (Cl. 9—17)

(Granted under the act of March 3, 1883, as
amended April 30, 1928; 370 O. G. 757.)

This invention relates to a pneumatic life preserver belt and has for an object to provide an improved life preserver of the pneumatic belt type.

A principal object of this invention is to provide a pneumatic life preserver belt which is carried around the waist of the wearer when in inactive position but which extends up to the chest when in inflated condition so as to provide flotation support sufficiently high on the wearer to insure the body being supported upright with the head out of the water safe against drowning.

A further object of this invention is to provide a pneumatic belt which may be worn continuously as a safety measure in inactive condition and is located about the waist of the wearer but which in an emergency can be inflated within fifteen seconds and will then occupy a position up near the chest of the wearer so as to provide flotation support substantially above the center of gravity of the wearer.

A further object of this invention is to provide a pneumatic belt which is easily adjustable so as to fit persons of different girths.

A further object of this invention is to provide a securing means for the pneumatic belt which securing means may be adjusted to fit persons of different girths and which in its preferred form is capable of supporting the weight of the person so that the person wearing the belt may be lifted from the water as by means of a boat hook through the securing means.

A still further object of this invention is to provide a pneumatic life preserver belt which may be worn about the waist in inactive position ready for any emergency at all times without substantial inconvenience to the wearer and which can be placed into active condition in a minimum time and at the same time is doubled in width so as to provide a greater amount of support about the trunk of the wearer up as far as the chest.

With the foregoing and other objects in view, the invention consists in the construction, combination and arrangement of parts hereinafter described and illustrated in the drawing in which:

Fig. 1 is a plan view of the preferred form of pneumatic life preserver belt of this invention ready to be applied about the trunk of the wearer.

Fig. 2 is a plan view of a similar life belt but with a slightly modified securing means showing the belt in the wide position, that is, the position

it would be opened up to when it is around the trunk of the wearer and is ready to be inflated.

Fig. 3 is a detailed view of the flat valve of the inflating tube.

Fig. 4 is a sectional view on line 4—4 of Fig. 3.

Fig. 5 is a sectional view on line 5—5 of Fig. 2, and

Fig. 6 is a sectional view on line 6—6 of Fig. 2.

There is shown at 10 the pneumatic life preserver belt of this invention. This belt 10 is made of a sheet of rubberized fabric folded over and vulcanized into a tube as along the seam 11 and vulcanized at its ends 12 and 13 to form a closed pneumatic belt. This belt 10 is provided with a fold line along the edge of the seam 11 so that the belt may be doubled over on the position shown in Figs. 1 and 5 to thereby occupy less area when secured about the waist of the wearer. Secured along the upper and lower edges of the belt 10 are a plurality of pairs of snap fasteners 14 and 15, thereby holding the belt in the folded over position shown in Figs. 1 and 5.

An inflating tube 16 is provided on what is the inner side of the belt 10 in folded position and what becomes the upper outer side when the belt is about a wearer and ready to be inflated. This tube 16 is held in position by a tube clip 17 and terminates in an air valve 18 adapted to be inflated by being inserted in the mouth of the wearer. The other end of the tube 16 is secured to a belt inlet 20 vulcanized through the belt 10 and provided with a flapper valve 21 secured to the perimeter of mouth 20 at four equally spaced points 19, thus permitting the air to pass only inwardly through this tube 16 as the belt is being inflated.

In order to permit the belt to be deflated again, as after use or after testing, a drain valve 22 of conventional construction is provided at one end of the tube 16. The securing means for holding the belt about the waist of the wearer shown in the preferred form in Fig. 1 consists merely of a canvas strap 23 provided at one end with a snap buckle 24 and the other end with a snap buckle means 25, adjustability in size being provided by a conventional take-up buckle 26 through which the strap 23 extends. In order to secure the strap 23 to the belt 10, the belt 10 is provided with a plurality of tubes 27 through which the strap 23 may be inserted, these tubes 27 consisting merely of rectangular patches which are cemented along two of their ends 28, thus providing tubes through which the strap may be placed. Instead of providing a long strap 23, a short strap 30 may be used as in Fig. 2, the short strap

30 being provided with the same take-up buckle 26' adjustable in size and is provided at both ends with a snap buckle 24'. In this case, however, a snap buckle ring 25' is secured by a patch 31 to a side of the belt 10 and additional snap buckle rings 25' now secured at and near the opposite end of the belt 10 by means of additional patches 31'.

In operation the belt is folded over to the position shown in Figs. 1 and 5, thereby placing the inflating tube 16 between the folds of the belt while the securing belt strap 23 or 30 is on an outer side of the folding belt and available for fastening about the waist of the wearer. When securing the belt to the wearer's trunk the securing strap 23 or 30 is placed next to the body of the wearer with the folded belt on the outside. If the pneumatic belt is somewhat large on the particular individual it is obvious that one end of the folded belt may be telescoped within the other end of the folded belt to provide a neater fit.

When necessary to use the belt in an emergency the folded over belt is grasped and pulled up to separate the snap fasteners 14 and 15, thereby bringing the inflating tube to the outer side of the belt with the upper fold about the chest while the air valve 18 is in a position closer to the lips ready for blowing up the belt. The belt may be inflated by a person of average size in about fifteen seconds, thereby providing all the support necessary to keep from drowning.

In the form shown in Fig. 1 a person may be assisted from the water by placing a boat hook

under the strap 23, for as above observed this strap 23 extends close about the trunk of the wearer with the life belt on the outer side thereof.

Other modifications and changes in the number 5 and arrangement of the parts may be made by those skilled in the art without departing from the nature of the invention, within the scope of what is hereinafter claimed.

The invention described herein may be manufactured and used by or for the Government of the United States of America for governmental purposes without the payment of any royalties thereon or therefor.

Having thus set forth and disclosed the nature 15 of this invention, what is claimed is:

A pneumatic life preserver belt comprising a pneumatic tube foldable along a longitudinal median line, securing means on said belt for holding said folded or unfolded belt about the trunk 20 of the wearer and an inflating tube on said belt, said inflating tube being located on the inner folded side of said belt, a tube clip on the inner side of said belt, said fold line being adapted to be placed upwardly when the belt is secured in position, said inflating tube having its free end detachably supported in said tube clip on the inner side of the upper fold whereby the upper fold 25 may be extended toward the chest of the wearer to bring the free end of said inflating tube nearer to the mouth of the wearer, said inflating tube 30 being of sufficient length for its free end to reach the mouth of the wearer.

EDWARD C. CRAIG.
